CHARLES L. ROBERTSON, OF PROVIDENCE, RHODE ISLAND.

Letters Patent No. 88,811, dated April 13, 1869.

IMPROVEMENT IN COMBS.

The Schedule referred to in these Letters Patent and making part of the same.

To all whom it may concern:

Be it known that I, CHARLES L. ROBERTSON, of the city and county of Providence, in the State of Rhode Island, have invented a new and useful Improvement in Combs; and I do hereby declare that the following specification, taken in connection with the drawings making a part of the same, is a full, clear, and exact description thereof.

The purpose of my invention is to produce a comb by the employment of a combination of materials and processes not before used for the purpose, whereby a new manufacture is made to result.

I first make what I call a "foundation" for a comb, (Figure 1,) the greater proportion of which shall be composed of paper or paper-stock.

By means of suitable cutting-machinery, the character of which any competent mechanic will understand, an article in the general form of a comb may be cut from thick paper, pasteboard, card-board, or from any of the manufactures from paper-pulp. Two or more of the thicknesses so obtained may be glued together by any suitable adhesive compound, and, if preferred, thicknesses of muslin or other cloth, cut also into the same general form, may be placed between such thicknesses of paper, or over the same, in order to stiffen the foundation.

The foundation so prepared may then be subjected to pressure between dies, to complete its outline or ornamental configuration, and to give to it the entire form of a comb.

Instead of making the foundation from the manufactured products referred to, it can be moulded from paper-pulp, and after being dried, subsequently stiffened by the application of cloth-layers, or not, as desired.

The manner of producing, moulding, or shaping the foundation is not essential, as various mechanical processes can be employed for this end. It is sufficient to enable the article hereinafter claimed as new to be produced by the next-described process, if essentially

a paper or paper-stock comb is employed for a foundation.

The next thing necessary to be done to complete the manufacture, is to coat the whole exterior surface of the foundation with a japanning or enamelling composition, of the character described in the Letters Patent granted to me, April 2, 1867, and develop the same by the application of heat, as many separate coatings being applied as shall be necessary to produce a smooth and lustrous finish.

For the manner of preparing and developing such enamelling composition, reference may be had to the description contained in the before-mentioned Letters Patent; but I wish it to be distinctly understood that I do not confine myself to the use of a composition of the same elements in the same proportions as described in said patent, but any other japanning composition, of the same general character, possessing like qualities, and capable, upon the application of heat, to develop lustre, may be employed.

The result of the processes before described, is a comb (Figure 2) which, although it has for its base, or foundation a material of short staple, which alone would be unsuitable for such article, when enamel-coated as described, will possess the qualities of toughness, flexibility, and elasticity, in as great a degree as combs made from rubber, horn, or shell. In point of beauty it will also rival these, while, in addition, it possesses the advantage of great lightness, and can be manufactured at an inconsiderable cost.

What I claim as my invention, and desire to secure by Letters Patent, as a new article of manufacture, is—

A comb, made by applying and developing a japanning or enamelling composition upon a foundation made principally from paper or paper-stock, the whole article being substantially as specified.
